UNITED STATES PATENT OFFICE.

JACK MINZOFF, OF SUGAR PINE, CALIFORNIA.

FIRE TONGS.

Application filed August 3, 1928. Serial No. 297,220.

This invention relates to tongs for handling hot articles and especially pieces of wood, coal and the like, used in open household fire places or heating stoves.

5 Heretofore, as far as I am aware, all tongs constructed for this purpose have employed a pair of substantially parallel arms pivoted independently of each other and requiring the use of both hands to manipulate the tongs 10 for enabling the lumps of coal, etc., to be engaged and grasped. Such an arrangement makes the tongs awkward to use and it is hard to get a good grip on a lump held between the jaws unless the arms are grasped 15 close to the jaws with the liability of the hands of the operator being scorched or burnt. Also with this construction it is impossible to turn the tongs through any great arc as is necessary when desired to reverse or invert a lump 20 of coal or the like which has been burnt only on one side, without taking a fresh hold on the tongs.

The principal object of my invention therefore is to improve the construction of tongs 25 of this general character so as to avoid the above inefficient and unsatisfactory operation by arranging the tong arms so that the tongs can be grasped, and the jaws properly moved to and from each other, by one hand only of 30 the operator and at a considerable distance from the jaws.

By means of this construction there is no danger of the hand being scorched or burnt, and the tongs may be easily moved and turned 35 in any direction and through a considerable arc by said one hand while holding a lump firmly engaged with the jaws. At the same time the tongs are no longer or heavier than the ordinary implement of similar character.

40 A further object of the invention is to produce a simple and inexpensive device and yet one which will be exceedingly effective for the purpose for which it is designed.

These objects I accomplish by means of 45 such structure and relative arrangement of parts as will fully appear by a perusal of the following specification and claims:

The figure on the drawing is a perspective view of my improved tongs, partly spread 50 or open.

Referring now more particularly to the characters of reference on the drawings, the figures 1 and 2 denote a pair of transversely separated overlapping arms pivoted together 55 intermediate their ends as at 3, for scissors-like movement.

At one end the arms are formed with flat jaws 4, the flat surfaces of which are positioned to engage each other and are parallel to the axis of the pivot. Beyond the pivot, 60 the arm 2 is somewhat longer than the arm 1 and at its outer end is formed with a substantially semi-circular bend 5 which projects outwardly relative to the plane of the other arm. At its corresponding end the arm 1 is 65 formed with a rigid ring or eye 6, which is bent to project away from the arm 2 and to lie in a transverse plane substantially at right angles to the longitudinal plane of said arm 1. The portion 7 of the arm 2 adjacent the 70 bend 5 is preferably spirally corrugated as shown and serves as the main handle engaged by the hand of the operator. The eye 6 is disposed relative to the length of this handle portion, and is of such size as to conveniently and comfortably receive the thumb of the hand engaged with the handle portion 7. In other words said eye 6 is located adjacent the inner end of the said handle portion. The bend 5, besides imparting an ornamental appearance to the device forms a seat 75 for the end of the hand, preventing the tongs from possibly slipping lengthwise out of the hand.

By means of this construction it will be 80 seen that a firm grip on one arm may be always had, while the other arm may be moved, so as to move the jaws to or from each other, by a normal movement of the thumb to and from the hand. Since this digit naturally has 85 a greater strength than any other one member of the hand, ample gripping strength and pressure on the jaws may always be obtained. Since the tongs are held solely by one hand, they can be easily turned in any direction by 90 a corresponding movement of the wrist, without slackening the pressure or letting go of any piece held between the jaws.

From the foregoing description it will be 95 readily seen that I have produced such a device as substantially fulfills the objects of the invention as set forth herein.

While this specification sets forth in detail the present and preferred construction of the device, still in practice such deviations from 100 such detail may be resorted to as do not form a departure from the spirit of the invention, as defined by the appended claims.

Having thus described my invention what I claim as new and useful and desire to secure 110 by Letters Patent is:

1. A tongs comprising a pair of arms piv-

oted together intermediate their ends, co-operating jaws on the arms at one end, a handle to fit the palm of a hand formed on one arm at the other end, and a member for engagement with a digit of the hand, formed on the corresponding end of the other arm.

2. A tongs comprising a pair of arms pivoted together intermediate their ends, co-operating jaws on the arms at one end, a handle to fit the palm of a hand formed on one arm at the other end, and an eye member for engagement with the thumb of the hand formed on the corresponding end of the other arm.

15 3. A tongs comprising a pair of arms piv-

oted together intermediate their ends, co-operating jaws on the arms at one end, a handle to fit the palm of a hand formed as a longitudinal portion of one arm at the other end thereof, and an eye for engagement with the thumb of the hand formed on the corresponding end of the other arm and disposed adjacent the end of the handle closest to the pivot.

4. A structure as in claim 3, in which said eye projects away from the handle and lies in a transverse plane substantially at right angles to the arm on which it is mounted.

In testimony whereof I affix my signature.

JACK MINZOFF.
